6 Claims. (Cl. 74—22)

This invention relates to a device for controlling the translational and rotational movements of a rod, and more particularly said device comprises means capable of signalling when said rod is positioned in either end-of-stroke position of its translational stroke.

An object of this invention is to provide a device of the kind referred to above, which is compact and self-contained within an outer closed shell, without any external members or rods having a notable bulk in the axial direction which often are affected by severe drawbacks in view of their exacting space requirements and which are particularly open to objection whenever it is desired to provide an efficient hydraulic sealtightness.

Another object is to provide a device in which said means adapted to signal the end-of-stroke positioning of said rod as regards its translational stroke form an integral unit with the means for controlling the rotation of the rod, by exploiting constructional components common to both control means.

Still another object is to provide a device having a minimum size and in which the movable members are protected and capable of being readily lubricated.

Yet another object is to arrange said signalling means in such a way that they comprise a member capable of being displaced through a short path, in either direction, beyond an intermediate position responsive to the fact that the rod is in either end-of-stroke position on completion of a translational travel, even of a considerable length.

The present device comprises a body having a cylindrical straightline bore a piston solidly affixed to a rod and positioned within said bore so as to be freely and rectilinearly displaceable therethrough and rotatable about its own axis with respect to said body, said rod projecting out of said body, the body, in correspondence with the point at which the rod comes out thereof, is fitted with sealtight means between said body and said rod, a shaft housed along a certain portion of its length within a cavity axially formed through said piston and said rod, sealtight means between said shaft and said rod, means adapted to lock said rod and shaft against mutual rotation yet permitting mutual axial displacements therebetween, means adapted to feed a pressurized fluid above and below said piston respectively, means to impart a rotational drive to said shaft, with the shaft projecting out of said body on the side away from that from which said rod protrudes and being mounted within said body so as to move freely in an axial direction by small incremental movements about an intermediate position and the portion of the shaft housed within said cavity of said rod being provided with abutments with which said rod interacts when thrust by said pressurized fluid towards

2

the maximum elongation position or towards the minimum elongation position with respect to said body, respectively.

In order that the structure of the inventive device may be better understood and the advantages stemming therefrom fully appreciated, a merely exemplary and nonlimiting embodiment of said device will be given hereinafter, reference being had to the accompanying drawing, wherein:

FIGURE 1 is illustrative of a lengthwise cross-sectional view of the device,

FIGURE 2 is a cross-sectional view taken along line II—II of FIG. 1, and

FIGURE 3 diagrammatically shows, partly in cross-sectional view, the end portion of the device with a rod, projecting therefrom, which supports a radar head.

Referring to the drawing, it can be seen that the device comprises a body 1 in which a cylindrical bore 2, having a circular cross-section is formed and in which a piston 3, solid with a rod 4 is mounted and the free end of the rod projects from the body 1 through a bore coaxial with the bore 2. The latter bore is provided with a bushing 5 and a sealtight ring 6. Piston 3 is allowed to rotate freely about its own axis in the bore 2 and be freely translated therein through a stroke whose length is a function of the length of the bore 2. Internally of and coaxially with the piston 3 and the rod 4 a cavity 7 is formed within which is housed, for a certain portion of its length, a shaft 8. In correspondence with the piston, tight seals 9 are provided between said piston and the wall of the bore 2 and between the piston and the surface of the shaft 8, respectively. In the wall of the means constituting the cavity 7 are formed two longitudinal grooves 10 within which are housed two noses or keys 11 projecting from the shaft 8 to which the noses are solidly affixed. Due to the shape and mutual positions of the grooves 10 and the noses 11, the shaft 8 and the rod 4 are allowed to be displaced axially but their relative rotation is impeded.

The shaft 8 is extended beneath and out of the piston 3 so as to protrude for a short distance from the body 1, through a bore formed in said body under the piston 3 and which is coaxial with the bore 2. As can be seen in the lower portion of FIG. 1, the shaft 8 is provided with an integral collar 12 sandwiched between two axially spaced perforated discs 13, each of which is urged by a pre-loaded spring 14, biased between an abutment in the body 1 and the disc. The effect of the springs is to maintain the shaft 8 in an intermediate equilibrium position. Beneath the springs 14, the shaft 8 has a grooved portion on which is mounted a wheel 15 with respect to which the shaft can effect axial displacements with the wheel being keyed to the shaft to rotate therewith. The wheel 15 is engaged by a worm 16 which, when is rotated by a suitable motor (not shown to simplify the showing), causes the wheel 15 and as a consequence the shaft 8 to rotate and, the latter, in turn, transfers the rotational drive to the rod 4 via the noses 11 engaging the longitudinal grooves 10. At the end of the portion of shaft 8 which projects from the body 1, a graduated disc type dial 17 is affixed, which, in cooperation with a pointer 18 enables the reading of the angle through which the shaft 8 and rod 4 have been rotated with respect to the body 1. Solidly affixed to said disc-type dial

is a second pointer 19 whose position with respect to two axially spaced notches 20 and 20' formed about the body 1 indicates whether the rod 4 is in its position of full extension or of minimum extension with respect to the body 1, as will be clarified hereafter.

In the body 1 a channel 21 is provided which establishes communication between a chamber existing beneath the lower face of the piston and a source of pressurized fluid, more particularly oil, upon actuation of flow control means which have not been shown for the sake of simplification. In substantially the same way, the source of pressurized fluid is placed in communication, via a channel 22, with a chamber formed above the piston between the outer surface of the rod and the circular surface of the cylindrical bore 2.

Let us assume now that it is desired to impart a translational motion to the rod 4 to displace the rod from the body 1. By admitting pressurized fluid from the channel 21 under the piston 3, said piston is thrust and displaced, non-rotationally, along the bore 2. As the piston has been lifted from the position shown in FIG. 1, bottom 23 of the cavity 7 no longer bears on the head of the shaft 8. The shaft 8 thrust by the springs, is restored to its intermediate position where it remains until such time as the rod 4, thrust by the pressurized fluid, has reached its top dead center position, i.e. the position of maximum extension from the body 1, thus effecting a translational movement which can even be of a considerable length. When the rod has reached its top dead center, the noses 11 are contacted and thrust by the end walls of the grooves 10 close to the piston. By so doing, the shaft 8 is thrust by the pressurized fluid in the same direction in which the rod has been displaced. The shaft is thus lifted from its intermediate position, causing the length of its section protruding below the body 1 to be increased, the pointer 19 being brought in correspondence with the notch 20' thus indicating that the rod has reached its top dead center.

As can be readily seen, the pointer 19 effects a very slight displacement from its intermediate position to indicate that the rod has reached its top dead center, irrespective of the length of the rod's stroke.

If it is desired to have the rod enter the body 1 again, no more pressurized fluid is sent to the channel 21, the fluid being conversely sent to the channel 22, so as to be operative upon the top of the piston, the latter being thus thrust towards the position illustrated in FIG. 1. As soon as he piston and the rod have moved from the top dead center position, the shaft 8, no longer pressed by said end wall of the grooves 10 acting on the noses 11, reverts to its intermediate position, where it remains until such time as the rod has reached its bottom dead center, i.e. the position shown in FIG. 1, wherein said rod is in the condition of minimum projection from the body 1. Under these conditions, the fluid 23 of the cavity 7 presses the head of the shaft 8, which latter is displaced from its intermediate position bringing the pointer 19 in registry with the notch 20 (FIG. 1) thus signalling a slight displacement indicative of the fact that the rod 4 has reached its bottom dead center.

Assuming now that it is desired to impart a rotational motion to the rod 4 about its own axis, irrespective of the fact that the rod is being translated or is at standstill in correspondence with either dead center position or in any intermediate position between the dead centers, a rotational motion is imparted to the worm 16 which rotates the wheel 15 and this, through the shaft 8, the noses 11 and the grooves 10, causes the rod 4 to be rotated. The angle through which said rod has been rotated with respect to the body 1 can be read on the dial 17 with the pointer 18.

The fields of application of a device such as described above can be numberless: an example has been shown in FIG. 3 where the device is an integral part of a radar installation, for example of the collapsible type, comprising a head 24 containing the electronic components, said

head being supported by the rod 4 by a double thrust bearing 25 and solid with a telescopic bar 26 which permits the translation with respect to the body 1 but prevents any rotation. The end of the rod 4 carries the radar antenna proper 27 which, in addition to being capable of translational movements, must also be capable of rotating or oscillating together with said rod.

The exemplary device illustrated herein is not limiting since it could be modified in numerous manners without departing from the scope of the invention. Thus the rotation control unit comprising the worm gear 15-16 can be replaced by a hydraulic motor. The indications that the dead centers have been reached as to the translation of the rod and its rotation can be derived electrically and transferred to a remote panel. Instead of having the bottom 23 of the cavity 7 abutting the head of the shaft 8 as the rod reaches its bottom dead center, one can have the end walls of the grooves 10, close to the bottom 23 of the cavity 7, abutting the noses 11: the dial 17 could be dispensed with or also said dial and the pointer 18 could be replaced by a graduation formed on the surface of the body 1, whereas the pointer 19, in addition to showing the attainment of the dead center position, could be used for reading the angle of rotation upon said graduation.

At any rate, the device according to the invention is very compact and wholly contained within the body 1 without any external rod or member, the movable components thus being protected from shocks and their lubrication convenient. Lastly, to indicate that the rod has reached its dead centers, the shaft 8 undergoes a slight axial displacement without occupying a large space.

I claim:

1. A device for controlling the translational and rotational movements of a rod; comprising a body having a cylindrical straightline bore, a rod, a piston, solidly affixed to said rod and positioned within said bore so as to be freely and rectilinearly displaceable therethrough and rotatable about its own axis with respect to said body, said rod projecting out of said body, sealtight means between said body and said rod, at the point at which the rod projects from said body, a shaft housed along a certain portion of its length within a cavity axially formed through said piston and said rod, sealtight means between said shaft and said rod, means for locking said rod and shaft against mutual rotation yet permitting mutual axial displacements therebetween, means for feeding a pressurized fluid above and below said piston, respectively, means for imparting a rotational drive to said shaft, said shaft projecting from said body at the end remote from that through which said rod projects, means mounting said shaft within said body so as freely to move in an axial direction by small incremental movements from an intermediate position, and abutments cooperable with said certain portion of said shank housed within said cavity when thrust by said pressurized fluid towards the maximum elongation position or, respectively, towards the minimum elongation position with respect to said body.

2. The device according to claim 1, wherein means for indicating the position of the shaft with respect to the body are provided at the end of said shaft projecting from said body.

3. The device according to claim 1, wherein said cavity formed axially in the piston and in the rod is provided with, at least in correspondence said rod, with longitudinal grooves wherein are housed in a freely slideable manner, noses projecting from said shaft to which said noses are solidly affixed.

4. The device according to claim 4, wherein said noses form an abutment with which an end wall of said groove coacts when the rod is thrust by said pressurized fluid to the maximum elongation position from said body, said noses providing another abutment with which the other end of said groove interacts, when said rod is thrust by

the pressurized fluid towards the position of minimum elongation from said body, said rod causing, when said abutments take place, the displacement of the shaft on either side of said intermediate position.

5. The device according to claim 1, wherein said means for feeding a pressurized fluid above and below said piston is respectively channels formed in said body and respectively communicating with said cylindrical bore above and below said piston, said channels being connected to a source of pressurized fluid, and flow control means for said fluid flowing to said channels.

6. The device according to claim 1 including two axially spaced pre-loaded springs, a collar solidly affixed to

said shaft located between said springs with said springs abutting said body and said springs and collar serving to hold such shaft in said intermediate position.
